UNITED STATES PATENT OFFICE

FRANK J. STAYTON, OF BIRMINGHAM, ALABAMA, ASSIGNOR TO BATTERTON COFFEE CO.
INC., A CORPORATION OF ALABAMA

DESIGN FOR A JAR

Application filed October 31, 1932. Serial No. 45,663. Term of patent 3½ years.

To all whom it may concern:

Be it known that I, FRANK J. STAYTON, a citizen of the United States, residing at Birmingham, in the county of Jefferson and State of Alabama, have invented a new, original, and ornamental Design for Jars, of which the following is a specification, reference being had to the accompanying drawing, forming a part thereof.

In the drawing,

Figure 1 is an elevation; and

Figure 2 is a top plan view of a jar embodying the features of my new design, and showing the raised ornamentation displayed on three sides of the jar.

I claim:

The ornamental design for a jar substantially as shown and described.

FRANK J. STAYTON.
